FOLDABLE PACK FOR FRAGILE ARTICLES

Ernest L. Shepard, Fairfield, Maine, assignor, by
 mesne assignments, to The Canal National
 Bank of Portland, Portland, Maine, a national
 banking association, and William B. Nulty,
 Portland, Maine, as trustees

Application January 6, 1950, Serial No. 7,037

Term of patent 14 years

(Cl. D58—13)

To all whom it may concern:

Be it known that I, Ernest L. Shepard, a citizen of the United States, residing at Fairfield, in the county of Somerset, State of Maine, have invented a new, original, and ornamental Design for Foldable Pack for Fragile Articles, of which the following is a specification, reference being had to the accompanying drawing, forming part thereof.

Fig. 1 is a top plan view of a foldable pack for fragile articles, showing my new design, the pack being open.

Fig. 2 is an end view of the pack shown in Fig. 1.

Fig. 3 is a front elevation of the pack with the cover in closed position, and

Fig. 4 is a sectional view of the pack taken on line 4—4 of Fig. 1.

I claim:

The ornamental design for a foldable pack for fragile articles, as shown.

ERNEST L. SHEPARD.
